UNITED STATES PATENT OFFICE.

GERARD SCHUMACHER, OF ANNISTON, ALABAMA.

DESIGN FOR A LIGHT-CLUSTER FOR STREET LAMPS OR POSTS.

43,482.

Specification for Design.

Patented Jan. 21, 1913.

Application filed May 22, 1912. Serial No. 699,078. Term of patent 7 years.

To all whom it may concern:

Be it known that I, GERARD SCHUMACHER, a citizen of the United States, residing at Anniston, in the county of Calhoun and State of Alabama, have invented a new, original, and ornamental Design for Light-Clusters for Street Lamps or Posts, of which the following is a specification, reference being had to the accompanying drawing, forming part thereof.

The figure is a perspective view of light

clusters for street lamps or posts, showing my new design.

What I claim is:—

The ornamental design for light clusters for street lamps or posts, substantially as shown.

GERARD SCHUMACHER.
